UNITED STATES PATENT OFFICE.

JAMES W. PEARCE, OF CHICAGO, ILLINOIS, ASSIGNOR TO GOODMAN MANUFACTURING COMPANY, OF CHICAGO, ILLINOIS, A CORPORATION OF ILLINOIS.

SYSTEM FOR MINING.

Application filed December 6, 1924. Serial No. 754,261.

This invention relates to improvements in systems for mining, and more particularly to systems where draft operated scraper loaders are used to gather the material from predetermined areas in the mine but leaving certain portions of the material as supports for the mine roof.

My invention is particularly adapted for use in coal mines where it is desirous to leave pillars or supports at various intervals 10 while the coal is being mined.

Among the objects of my invention is the provision of a system whereby scraper loaders are advantageously used in gathering 15 loose material as it is dislodged along certain working faces, and transported for loading upon mine cars.

More specifically the object is to provide a working plan or system wherein the material is worked out along relatively long 20 working faces so as to require a minimum number of changes in the position of the scraper loading apparatus including the draft rope anchors and power devices as well 25 as the loading chutes or platforms adjacent the mine cars where final loading is accomplished.

Scraper loaders have heretofore been used more or less extensively as a means of gathering or transporting loose material from the working faces of the mine to be loaded 30 on mine cars. One of the prerequisites of successful operation of the scraper loaders, especially where it is desired to leave pillars 35 at certain intervals, is the provision of a system wherein a maximum area can be gathered and loaded with a single setting of the loading apparatus. In scraper loader systems of the class herein referred to, the 40 scraper is of any desired form capable of gathering loose material and is operated by draft ropes trained over guides or sheaves anchored in proper positions, the draft ropes being operated by a winding engine or hoist in position to move 45 the scraper reciprocably between the working face and the loading station at an entry where the mine cars are loaded. One of the most efficient and satisfactory methods heretofore employed in connection with 50 scraper loaders is the so-called panel system of mining in which cross entries substantially at right angles to each other are driven in the material to be mined so as to form substantially rectangular blocks. Tracks are

laid along certain of the entries and cross entries and the scraper loader apparatus is positioned at such loading track to load out material through an entry at right angles to said loading track, the working face extending along one or more blocks and being progressed laterally in a line substantially parallel with the loading entry. In systems of this kind, however, it is necessary to change the position of the loading chute and the hoist quite often as the loading operation 60 proceeds in each entry. It is also more or less difficult to provide for pillars spaced the required distance apart, it being understood that the blocks are usually in elongated form, 65 and the pillar which would be left along the center of such a block is unnecessarily long, thus resulting in a loss of material which might otherwise be obtained. As will be seen from the following description my improved system contemplates a modified form 70 of the panel system of mining in which the working face is progressed upon lines inclined to the loading entry, the initial loading being done at a position remote from the loading station and on either side of the loading entry. The material is loaded out upon predetermined lines so as to leave one or more pillars of pyramidal or inverted V 75 form, thus making the pillars relatively shorter but wider than would be possible in case the pillar was narrow and rectangular in shape, as in the ordinary panel system 80 of mining already described.

My invention may best be understood by reference to the accompanying drawings, in which:

Figure 1 is a diagrammatic view of a section of a coal mine being worked in accordance with the system forming the subject 95 matter of my invention;

Figure 2 is a detailed view of the initial operation in opening up a section of the mine;

Figure 3 is a view similar to Figure 2 but 100 in which the mining operation has progressed through certain stages of operation.

Figure 2 illustrates the initial operation in carrying out my system. Cross entries 105 10, 10, and 11, 11 have been driven substantially at right angles to each other to form blocks 12, 12. In the form shown, these blocks are preferably elongated in the direction of movement of the scraper. Certain of the cross entries, as for instance 11a, 11b

and 12^a, are haulage entries, being provided with tracks 13, 13 for coal cars 14, 14. The scraper is indicated at 15 having head rope 16 and a tail rope 17 operatively connected to the winding engine 18. The scraper and winding engine are of the usual form and need not be described in detail. The tail rope 17 is trained over sheaves 19 and 20 anchored in the end cross entry 10, the sheave 19 being at the juncture of the cross entries 10 and 11 in which the loading operation is to proceed. The second sheave 20 is positioned to one side of the entry as indicated in dotted lines in Figure 2 in which position the scraper is adapted to pass along the extreme upper corner of the adjacent top block 12. The mining of the block is then started along a working face 24 substantially parallel with the path of movement of the scraper as it moves around the extreme corner of the block. As each cut is made along the working face, the scraper is used to gather the coal and transport it to the loading chute 25 adjacent the haulage entry 12^a for loading in the mine cars 14. As the mining operation proceeds the working face 24 will manifestly be rapidly extended to the position indicated in full lines by the working face 25 in which the entire length of the block is being worked. As the working face is advanced, of course, the corner sheave 20 is moved outwardly to maintain the scraper in its desired loading relationship with respect to the face. When the mining has reached a point substantially midway of a block, the sheave 20 may be changed to the opposite side of the loading entry 11, so as to load out a similar portion of the right hand block as shown in Figure 2, thus making a substantially V shaped area. If it is desired to leave two pillars in one of the blocks, as for instance in the left hand block 12, the sheaves 19 and 20 are shifted toward the haulage entry in the position shown in Figure 3, and the loading out proceeds upon a new working face 26 formed in staggered relation as clearly shown in the left hand panel in the latter figure. In this case, however, a slice is also taken off along a new working face 27 in the second panel below the upper block 12. The right hand panel in Figure 3, as shown herein, is formed in a large pillar extending the full length of the block which may be desirable in the present instance since this is immediately adjacent the main haulage entry 11^a in which tracks extend and which should be maintained by means of a substantial support.

It will now be clear that the mining operation may proceed further by moving the sheaves 19 and 20 to a new position in the center cross heading 10 shown in Figure 3, and by advancing the working faces 27 and 29 on opposite sides of the working entry.

The cleared area will extend to the right hand sides of the areas 30, 31, and 32 which are left to form triangular pillars at the right hand side of the initial loading area and the areas 34 and 35 which will form rectangular pillars at the left hand side of the area. 70

It will be understood, however, that it is desirable to limit the progressive movement of the sheaves 19 and 20 toward the loading chute so that the path of movement of the scraper does not take too great an angle in its approach to the loading chute. Consequently, the operations shown in Figure 3 are preferably discontinued when the working faces extend along the lines indicated at 27^a and 29^a. When this stage is reached, further loading operations from this block are continued by moving the loading apparatus to a more remote or retracted position 85 along the same loading entry 11, as will be better understood by reference to Figure 1, showing the operation of the system as applied to a larger area of the mine and in which the operations have proceeded to a further degree. In this view an additional tier of blocks above those illustrated in Figures 2 and 3 are being worked out from the haulage entry 12^a. It will be seen that the first loading entry 11 has been completely 90 worked out down to the inclined working faces 27^a and 29^a in the lowermost tier of blocks, while similar operations have been carried out in the second loading entry 11 so as to leave similar pyramidal pillars 30^a, 31^a, 30 and 31, and a larger pillar 32^a, the latter pillar being in the bottom tier. The scraper apparatus is shown in the third loading entry in which work has progressed to completely form small pillars in the upper tier and partially form the small pillars in the second tier of blocks. From the various diagrams and descriptions just preceding, it will be manifest that my system may be applied to a varying number of blocks, depending upon working conditions, in each case leaving pillars at any desired distance apart. It will be further understood that in the case of the larger pillars such as shown in full lines in Figure 1, and designated by numeral 32^a, material may be removed from this pillar so as to form two smaller pillars 32 and 33 indicated in dotted lines, when the scraper apparatus is moved to a lower tier of panels and the loading is done at a more remote point, say two or three tiers below that shown in the drawings. 110

With my improved system the line of movement of the scraper may be maintained 125 in substantially straight lines between the moving chute and the movable guide 20, thus eliminating the necessity of changing the course of movement of the scraper to any great degree. This is a distinct advantage 130

in the operation of scrapers of this character in view of the manifest difficulty of providing satisfactory means for turning or changing the forward course of movement of the scraper. My system furthermore affords considerable variation in the manner in which it may be carried out either in the shape of the blocks, the number of blocks to be worked at one time, or the shape or/and size of the pillars which may manifestly be varied widely, depending upon the working conditions. The development of my improved system is such that it is unnecessary to clean out material from corners, as in room and pillar methods.

I claim as my invention:

1. The method of mining which consists in initially driving a plurality of substantially parallel and intersecting cross entries to form rectangular blocks, removing the material from the blocks by scraper loading devices extending along working faces formed in adjacent parallel working entries and loading in transportation entries intersecting said working entries, removing the material along predetermined staggered working faces on opposite sides of each working entry and connecting the working operations in adjacent working entries to leave pillars of pyramidal or inverted V shaped form along the central portions of each of the blocks.

2. The method of mining which consists in initially driving a plurality of substantially parallel and intersecting cross entries to form rectangular blocks, removing the material from the blocks by scraper loading devices extending along working faces formed in adjacent parallel working entries and loading in transportation entries intersecting said working entries, removing the material along predetermined staggered working faces on opposite sides of each working entry, loading at one point from a plurality of tiers of blocks, and connecting the working operations in adjacent working entries to leave pillars of pyramidal or inverted V shaped form along the central portions of each of the blocks.

3. The method of mining which consists in initially driving a plurality of substantially parallel and intersecting cross entries to form rectangular blocks, removing the material from the blocks by scraper loading devices extending along working faces

formed in adjacent parallel working entries and loading in transportation entries intersecting said working entries, the rope guide devices of the scraper loader being initially placed to remove the material along the working faces inclined outwardly from the working entry with the widest portion thereof at a point farthest removed from the point of loading, until a predetermined amount of material has been removed, and thereafter shifting the rope guides to a point nearer the point of loading and removing a further section of working face on lines substantially parallel to the initial inclined working faces on either side of the entry whereby the resultant wall on opposite sides of a working entry is left in staggered form with alternate peaks and depressions, and thereafter completing similar operations in the next adjacent working entry to form a plurality of pillars in pyramidal or inverted V shaped form remaining along the central portions of each of the blocks.

4. The method of mining which consists in initially driving a plurality of substantially parallel and intersecting cross entries to form rectangular blocks, removing the material from a plurality of tiers of blocks by loading in transportation entries intersecting said working entries, the rope guide devices of the scraper loader being initially placed to remove the material along the working faces inclined outwardly from the working entry, with the widest portion thereof at a point farthest removed from the point of loading, until a predetermined amount of material has been removed, and thereafter shifting the rope guides to a point nearer the point of loading and removing a further section of working face on lines substantially parallel to the initial inclined working faces on either side of the entry whereby the resultant wall on opposite sides of a working entry is left in staggered form with alternate peaks and depressions, and thereafter completing similar operations in the next adjacent working entry to form a plurality of pillars in pyramidal or inverted V shaped form remaining along the central portions of each of the blocks.

Signed at Chicago, in the county of Cook and State of Illinois, this 28th day of November, A. D. 1924.

JAMES W. PEARCE.
